(57) CLAIM

The ornamental design for a hand held detailing brush, as shown and described.

DESCRIPTION

FIG. 1 is a perspective view of a hand held detailing brush, showing our new design;

FIG. 2 is a side elevational view thereof, the other side being a mirror image thereof;

FIG. 3 is a front elevational view thereof;

FIG. 4 is a rear elevational view thereof; and,

FIG. 5 is a top plan view thereof, the bottom having a brush surface in a duplicate plan form as the top view.

FIGS. 2-5 are shown on a reduced scale.
